(57) **CLAIM**

The ornamental design for a base unit for carpet extractor, as shown and described.

DESCRIPTION

FIG. 1 is a perspective view of a base unit for carpet extractor showing our new design;

FIG. 2 is a perspective view thereof;

FIG. 3 is a left side elevational view thereof;

FIG. 4 is a front elevational view thereof;

FIG. 5 is a right side elevational view thereof;

FIG. 6 is a rear elevational view thereof;

FIG. 7 is a top plan view thereof;

FIG. 8 is a bottom plan view thereof; and,

FIG. 9 is a perspective view thereof with a nozzle portion shown in a raised position to allow removal of a recovery tank from the base unit.

While portions of the base unit are not visible in FIG. 1, the entire base unit is shown in FIG. 2.

The carpet extractor parts shown in broken lines in FIGS. 1 and 9 are shown for illustrative purposes only and form no part of the claimed design.

The portions of the interior details not completely shown in FIG. 9 form no part of the claimed design.
